UNITED STATES PATENT OFFICE.

JOHN WILLIAMS MABBS, OF CHICAGO, ILLINOIS.

ELECTRIC ELEVATOR.

SPECIFICATION forming part of Letters Patent No. 657,782, dated September 11, 1900.

Application filed July 26, 1897. Serial No. 646,032. (No model.)

To all whom it may concern:

Be it known that I, JOHN WILLIAMS MABBS, of Chicago, in the county of Cook and State of Illinois, have invented certain new and useful Improvements in Electric Elevators; and I do hereby declare that the following is a full, clear, and exact description thereof, reference being had to the accompanying drawings, and to the letters of reference 10 marked thereon, which form a part of this specification.

This invention relates to electric elevators.

One object of the invention is to provide a construction of electrically-operated elevator 15 which is simple, economical, and efficient and wherein the motor and its supporting-frame and associated parts form a counterbalance for the car.

Other objects of the invention will appear 20 more fully hereinafter.

The invention consists, substantially, in the construction, combination, location, and arrangement of parts, all as will be more fully hereinafter set forth, as shown in the accompanying drawings, and finally pointed out in 25 the appended claims.

Referring to the accompanying drawings and to the various views and reference-signs appearing thereon, Figure 1 is a view in side 30 elevation, parts being broken, of an apparatus constructed in accordance with the principles of my invention. Fig. 2 is an end view of the counterweight-frame which supports the motor, showing the relation of the 35 gearing, the said frame being removed from its guides. Fig. 3 is a transverse section on the line 3 3, Fig. 1, of the counterweight-frame and its guides, showing in top plan the arrangement of gearing. Fig. 4 is a bottom 40 plan view of the counterweight-frame and motor, showing the application of a brake device. Fig. 5 is a detail sectional view of the brake mechanism on the line 5 5, Fig. 4. Fig. 6 is a detail view, in side elevation, of 45 the brake mechanism.

The same part is designated by the same reference-sign wherever it occurs throughout the several views.

In the drawings reference-sign B designates the car; H, the hoisting-cable connected thereto; I, the guide-sheave over 50 which the hoisting-cable operates, and A the

guides forming the elevator shaft or well and in which the car operates. These parts may be of the usual or any well-known or convenient construction and arrangement, and the specific details of construction thereof form no part of the present invention and need not be described in detail herein. The hoisting-cable is connected at one end to the car and 55 after passing over the guide-sheave I is formed into a bight in the usual manner, and the other end thereof is anchored or fastened, as at J, to a fixed beam or in any other suitable or convenient manner. 60

In suitable relation to the elevator shaft or well are arranged the independent vertical guides C C. These guides may be in the form of standards, beams, posts, columns, or the like. In the particular form shown, to which, 65 however, the invention is not limited or restricted, I employ I-beams placed with their webs parallel to each other, and said independent guides are spaced a suitable distance apart to form a guideway therebetween. 70 Mounted to operate in the guideway thus formed is a frame D, which I will designate the "counterweight-frame." This frame is provided on the opposite sides thereof and at suitable distances apart with lugs or projections e³ e³, arranged to engage suitable flanges C' C', formed on or suitably secured to the inner or juxtaposed faces or sides of the guides C C, thereby guiding the counterweight-frame in the vertical movements 75 80 85 thereof in its guideway. In the upper end of the counterweight-frame is journaled a sheave G, adapted to be received in the bight formed in the hoisting-cable, as above described, whereby the counterweight-frame is 90 supported by and suspended from said bight of the hoisting-cable, as clearly shown in the drawings. Racks (indicated at c c, Fig. 1) are formed on or secured to the opposite sides or edges of each guide C, the racks on each 95 guide presenting outwardly or away from each other, as clearly shown in Fig. 3. Thus I employ two guides C C, spaced a suitable distance apart, between which operates the counterbalance-frame D, and each guide is 100 provided on the respective edges or sides thereof with outwardly-presenting racks. In suitable diverging arms or bearings D' D', formed on the counterweight-frame, are jour-

naled shafts d d , said shafts being arranged to extend transversely of the counterweight-frame in substantially-parallel relation. At each end of each transverse shaft d d is mounted a pinion D^3 . The shafts d d are respectively arranged on opposite sides of the counterbalance-frame and are spaced a sufficient distance apart for the pinions D^3 on corresponding ends thereof to engage and intermesh with the racks c on the opposite sides or ends, respectively, of the guides C C —that is to say, the pinions D^3 on the ends of one shaft d will engage the racks c facing or presenting in one direction from the guides C C , respectively, while the gears D^3 on the ends of the other shaft will engage the corresponding racks c facing or presenting in the opposite direction from the other sides or edges of said guides, as clearly shown in Fig. 3. Longitudinally arranged with respect to the counterweight-frame and journaled in suitable bearings e e' e^2 , formed in said frame, is a shaft F' , upon which is formed or otherwise mounted or secured a worm F^2 . Upon each of the transverse shafts d and at a point intermediate the pinions D^3 thereon is a worm-gear D^2 , arranged to intermesh with and to be driven from worm F^2 , the arrangement being such that the shaft F' passes between shafts d d , and the worm-gears D^2 D^2 engage the driving-worm F^2 at diametrically-opposite points. The armature F of an electric motor (designated generally by reference-sign E) is mounted on shaft F' , the commutator of such armature being indicated at f . The field of the motor comprises a frame or yoke E' , which is mounted upon or may form part of the counterweight-frame and upon which are mounted the field-magnets E^2 . Current may be supplied to the motor in any convenient or well-known manner, the means herein shown consisting of a flexible conductor N . The motor may be controlled from the car in the usual or any well-known or convenient manner familiar to persons skilled in the art.

It will be understood from the foregoing description that the counterweight-frame, carrying the motor, the operating-gears, and the sheave G , is suspended in the bight of the hoisting-cable and has a vertical travel between the independent guides C C , such travel being imparted to such frame through the arrangement of racks and pinions and their driving-gears from the motor carried by said frame, and that such travel effects the raising or lowering of the car, in the arrangement shown the car rising as the counterweight-frame descends and the car descending when the counterweight-frame ascends, and therefore the counterweight-frame, together with the driving mechanism and motor carried thereby, constitutes a counterweight for the car, and in practice I so regulate the weight of the counterbalance-frame and the parts supported or carried thereby as to balance the weight of the car

without a load or the weight of the car with an average load, so that the work to be done by the motor will be expended in merely overcoming friction when the weight of the car and its load is approximately the same as that of the counterbalance-frame and the parts supported by it. Of course any desired relation may be established between the weight of the car and its load, on the one hand, and that of the counterweight-frame and the parts supported thereby, on the other hand, and this relation may be varied to secure the desired results.

Where a bight is formed in the cable, as in the construction shown, the counterweight will have a travel equal to one-half of that of the car. Of course it is to be understood that any other relation of travel of the car and the counterweight-frame may be adapted by suitably varying the size and number of the sheaves in a manner well known to persons skilled in this art.

In connection with the construction and arrangement of hoisting-motor as above described I employ a brake through which the motor may be controlled. In order to render the brake automatic in its action, I arrange the same in the motor-circuit to be operated by the same current. A simple, convenient, and efficient brake is disclosed in the drawings, and comprises a brake-wheel I' , about which is arranged a brake-strap I^2 . The ends of this strap are respectively connected to the arms of a bell-crank lever I^3 in such manner that when said lever is rocked in one direction the brake-band is tightened upon the periphery of brake-wheel I' and when said lever is rocked in the opposite direction the brake-band is released. The bell-crank lever I^3 may be rocked in any suitable manner automatically to set or release the brake-band from the brake-wheel. I have shown a simple and efficient means for accomplishing this result, wherein the lever I^3 is suitably connected through a link K' with the core K of a solenoid J , said solenoid being included in the motor-circuit, and the arrangement is such that when current is supplied to the motor the solenoid is energized, thereby causing the core K to move in a direction to release the brake-band, and when current is cut off from the motor the core of the solenoid moves in the opposite direction to cause the brake-band to grip the brake-wheel. The movement of the solenoid-core, due to the energization of the solenoid, may be opposed in any suitable or convenient manner, whereby when the flow of current through the solenoid is interrupted said core is returned to its normal position. A simple and efficient arrangement for securing this result is shown, wherein a spring M is interposed between the core K and a plate L , carried by rods l l , the latter being connected to a frame L' , which is carried by a bracket E^3 , forming a part of a depending arm E^2 H' , the counterweight-frame forming a support for the solenoid.

The movements of the solenoid may be guided by means of a rod K², working through an opening in said plate L. Thus the tension of the spring M is applied in opposition to

- 5 the movement of the core K when the solenoid is energized and operates to return said core. If desired, the motor-shaft may be provided with shoulders to bear against the bearings e e' e² to form thrust-bearings to
 10 prevent endwise displacement of said shaft, thereby preventing derangement of the relative positions of worm F² and worm-gears D², which intermesh therewith. It is evident, however, that any usual, convenient, or well-known form of bearing may be employed.

By the arrangement above described, wherein the worm-gears D² intermesh at diametrically-opposite points with the worm F², I secure an exceedingly efficient and steady operation of the hoisting-motor, and by reason of the arrangement of the transverse shafts d with the pinions D³ at each end thereof intermeshing with the oppositely faced or presented racks and the arrangement of the driving-shaft F' between said shafts, and with the worm-gears D² intermediate the ends of said shafts and intermeshing with the worm F² on opposite sides, lateral vibration and consequent binding of the counterweight-frame in its guides are prevented and a smooth easy-running movement of said frame is secured. This I consider a most important feature of my invention, resulting from the construction and arrangement as above set forth.

35 A construction such as above set forth is exceedingly economical and efficient in operation. By suitably proportioning the weight of the counterweight-frame and the parts supported thereby to that of the car and its load 40 only a comparatively small amount of work is required to be done in effecting the hoisting or lowering of the car, and this work is applied through the most powerful form of mechanism, and by the arrangement of two transverse shafts one on one side and the other on the other side of the guideway in which the counterweight-frame travels lost motion or slipping of the gearing is prevented.

It is obvious that the guideway in which 50 the counterweight-frame works may be arranged in any suitable relation with respect to the elevator well or shaft to suit any exigency of available space in the building in which the elevator is to be erected.

55 Many changes and variations in the details of construction and arrangement of parts would readily occur to persons skilled in the art and still fall within the spirit and scope of my invention. I do not desire, therefore, 60 to be limited or restricted to the exact details of construction and arrangement shown and described; but,

Having now set forth the object and nature of my invention and a construction embodying the principles thereof and having explained such construction, its purpose, function, and mode of operation, what I claim as

new and useful and of my own invention, and desire to secure by Letters Patent of the United States, is—

70

1. In an electric elevator, a car, a hoisting-cable therefor, a motor suspended from said cable and forming a counterweight for the car, and gearing actuated by said motor for raising and lowering the car, as and for the purpose set forth.

2. In an electric elevator, a car, a hoisting-cable therefor, an electric motor suspended from said hoisting-cable and forming a counterweight for the car, a guideway for said motor, and gearing actuated by said motor for raising and lowering the car, as and for the purpose set forth.

3. In an electric elevator, a car, a hoisting-cable therefor, a motor suspended from said cable and forming a counterweight for the car, a guideway in which said motor operates, a rack carried by said guideway, and a gear actuated by said motor and engaging said rack for raising and lowering the car, as and for the purpose set forth.

4. In an electric elevator, a car, a hoisting-cable therefor, a frame suspended from said cable and forming a counterweight for the car, a motor carried by said frame, a guideway in which said frame operates, and gearing operated by said motor for raising and lowering the car, as and for the purpose set forth.

5. In an electric elevator, a car, a hoisting-cable therefor, guides in which the car operates, independent guides arranged to form a guideway, a frame arranged between said independent guides and engaged on opposite sides thereof with said guides, said frame connected to said hoisting-cable and forming a counterweight for the car, a rack carried by each independent guide, a shaft arranged in suitable bearings in said frame and disposed transversely thereof, pinions carried at each end of said shaft and respectively arranged to engage said racks, and a motor carried by said frame for rotating said shaft, whereby said counterweight-frame is caused to travel to raise or lower the car, as and for the purpose set forth.

6. In an electric elevator, a car, a hoisting-cable therefor, guides in which the car operates, independent upright guides arranged to form a guideway, a frame arranged between to be engaged on opposite sides by said independent guides, said frame connected to said hoisting-cable to form a counterweight for said car, racks carried by said independent guides, gearing carried by said frame and arranged to engage said racks, and a motor carried by said counterweight-frame for driving said gearing, as and for the purpose set forth.

7. In an electric elevator, a car, a hoisting-cable therefor, a guideway for the car, guides arranged to form an independent guideway, a frame arranged between to be engaged on opposite sides thereof by said guides, said

- frame connected to said hoisting-cable to form a counterweight for the car, a pair of racks arranged on each guide, the members of each pair of racks arranged on opposite sides of their guide, and presenting in opposite directions, a pair of shafts suitably journaled in said frame and transversely disposed with reference to and respectively arranged on opposite sides of said guides, a pinion mounted on each end of each shaft, said pinions respectively engaging corresponding racks on said guides, and a motor carried by said frame and arranged to drive said gears, as and for the purpose set forth.
- 15 8. In an electric elevator, a car, a hoisting-cable therefor, a guideway in which the car operates, a frame connected to said cable, and forming a counterweight for the car, independent guides between which said frame is arranged to operate, said guides engaging said frame on opposite sides, a rack carried by each guide, a transverse shaft journaled in said frame and carrying a pinion at each end thereof, said pinions respectively engaging said racks, a worm-gear mounted on said shaft intermediate the ends thereof, a motor carried by said frame, a worm carried by the shaft of said motor, said worm arranged to engage and drive said worm-gear, as and for the purpose set forth.
- 25 9. In an electric elevator, a car, a hoisting-cable therefor, a guideway in which the car operates, a frame connected to said cable and forming a counterweight for the car, independent guides between which said frame is arranged to operate, said guides engaging said frame on opposite sides thereof, a rack carried by each guide, a shaft carried by said frame and transversely arranged with respect thereto, a pinion mounted on each end of said shaft, said pinions respectively engaging said racks, a worm-gear mounted on said shaft intermediate the ends thereof, a shaft journaled in said frame longitudinally thereof and carrying a worm arranged to engage and drive said worm-gear, and a motor carried by said frame for rotating said shaft, as and for the purpose set forth.
- 35 10. In an electric elevator, a car, a hoisting-cable therefor, a guideway in which said car operates, a frame connected to said cable and forming a counterweight for said car, guides spaced a distance apart to form an independent guideway, said frame operating in said guideway and engaged on opposite sides by said guides, oppositely-presenting racks respectively arranged on opposite sides of each guide, a pair of shafts journaled transversely in said frame and arranged to extend respectively on opposite sides of said guides, a pinion mounted on each end of each shaft, said pinions respectively engaging corresponding racks, a worm-gear mounted upon each transverse shaft intermediate the ends thereof, a

drive-shaft arranged between said shafts and carrying a worm arranged to engage and drive both of said worm-gears, and a motor carried by said frame for rotating said drive-shaft, as and for the purpose set forth.

11. In an electric elevator, a car, a hoisting-cable therefor, a guideway in which the car operates, a frame connected to said cable and forming a counterbalance for the car, guides arranged a distance apart to form an independent guideway for said frame, said guides engaging said frame on opposite sides, racks carried by said guides, transversely-arranged shafts carried by said frame and arranged to extend on opposite sides, respectively, of said guides, pinions carried by said shafts and arranged to engage said racks, a worm-wheel mounted on each transverse shaft, a drive-shaft journaled in said frame and arranged to extend between said transverse shafts, a worm mounted thereon and arranged to engage at diametrically-opposite points thereof with said worm-gears, and a motor carried by said frame for rotating said drive-shaft, as and for the purpose set forth.

12. In an electric elevator, a car, a hoisting-cable therefor, a frame connected to said cable and forming a counterweight for the car, guides between which said counterweight-frame operates, said guides engaging said frame on opposite sides thereof, racks carried by said guides, gearing carried by said frame for engagement with said racks, a motor mounted on said frame for actuating said gearing, and an electrically-operated brake arranged in the motor-circuit, whereby when current is supplied to the motor the brake is automatically released, and when the motor-circuit is broken the brake is set, as and for the purpose set forth.

13. In an electric elevator, a car, a hoisting-cable therefor, a frame connected to said cable and forming a counterweight for the car, guides spaced a distance apart to form a guideway in which said frame is adapted to operate, said guides engaging said frame on opposite sides thereof, racks carried by said guides, gearing carried by said frame for engagement with said racks, a motor carried by said frame for operating said gear, a solenoid arranged in the motor-circuit, and a brake for said motor arranged to be released when said solenoid is energized and to be applied when said solenoid-circuit is broken, as and for the purpose set forth.

In testimony that I claim the foregoing as my invention I affix my signature, in presence of two witnesses, this 23d day of July, A. D. 1897.

JOHN WILLIAMS MABBS.
